REINFORCED ABRASIVE ARTICLE MOUNTED
ON A BACKING PLATEWilliam Maxwell Wheildon, Jr., Framingham,
Mass., assignor to Norton Company, Worcester,
Mass., a corporation of Massachusetts

Application July 1, 1943, Serial No. 492,992

2 Claims. (Cl. 51—209)

This invention relates to a reinforced abrasive article mounted on a backing plate, and more particularly to segments and disks which are mounted on steel backing plates and arranged for grinding on their flat faces.

Grinding disks and abrasive segments have been heretofore of abrasive grains, such as crystalline alumina and silicon carbide, bonded by suitable bonds, such as magnesium oxychloride. This particular type of bond has certain desirable characteristics for grinding purposes, but the bonded material may crack under the strains and stresses of the grinding operation; hence it is desirable to reinforce the abrasive body by means of a wire mesh. Various problems have been presented in securing such an abrasive body on the metal backing disk which is mounted on the driven spindle of the machine. It has been found that when the abrasive material is secured to the metal by means of vulcanized rubber, the temperature of curing the rubber, which may be around 160° C., tends to damage the abrasive body. It has also been proposed to secure the abrasive body to a backing plate by means of screws inserted through the wire mesh and embedded in the abrasive, but the clamping pressure against the wire mesh or the abrasive sets up stresses that tend to weaken the wheel.

It is a primary object of this invention to overcome such problems and to provide a reinforced abrasive segment or grinding disk which is secured substantially integrally to a backing plate.

A further object of the invention is to provide a reinforced abrasive structure mounted on a metal backing plate in which the reinforcement is rigidly secured to the backing plate and the surrounding abrasive is interlocked with and held securely in position by means of the reinforcement. Further objects will be apparent in the following disclosure.

In the accompanying drawing, which illustrates a preferred embodiment of my invention:

Fig. 1 is a perspective view, partly broken away, showing a set of abrasive segments permanently mounted on a steel plate; and

Fig. 2 is a fragmentary section through one of the segments and its supporting plate.

In accordance with my invention, I propose to make an abrasive segment or an abrasive disk of a body of suitably bonded abrasive grains mounted on a metal plate and secured thereto by a reinforcing wire mesh which is in turn rigidly secured to the metal plate. The drawing shows a plane faced grinding wheel made of a set of abrasive segments mounted on separate metal

backing plates which are arranged as an annulus on and secured to a single supporting metal disk. Each segment may comprise an abrasive body 10 mounted permanently on a steel plate 12 and rigidly secured thereto by a reinforcing wire mesh 14. A set of steel plates 12 and the associated abrasive bodies are suitably shaped to provide an abrasive annulus having the top surfaces of the abrasive bodies lying in a plane. Each of the metal plates 12 is adapted to be mounted on a steel backing plate 16 which is in turn suitably connected to a driving spindle 18 as by means of bolts passing through the bolt holes 20 of the plate and engaging a flanged head on the spindle. 10 The abrasive body may be made of a suitable material, such as silicon carbide or crystalline alumina grains, bonded by a suitable bond, such as magnesium oxychloride. The abrasive body may comprise various types of compositions. For example, a satisfactory abrasive segment may be made of 45 pounds of crystalline alumina grains of desired grit size bonded into an integral mass by means of a cement formed of 9.7 pounds of magnesia wetted by 5.7 pounds of an aqueous solution of magnesium chloride having a specific gravity of 1.18. This mass of grains and bond may be suitably mixed and tamped in a mold to form the abrasive body after which it is allowed to harden for a suitable period of time. 15 20 25 30 35 40 45 50 55

As a reinforcement, I proposed to employ a wire mesh or other equivalent foraminous or reticulated material. I prefer a wire cloth or an open mesh body known as expanded metal which is embedded in the abrasive mass and makes a strong reinforcement and provides many interlocking surfaces for holding the abrasive body in place. This wire mesh is embedded in the lower portion of the abrasive segment or disk as by placing it initially in the mold and tamping the mixture of grains and bond around the mesh, thus forming a rigid and substantially integral body.

The primary feature of my invention comprises securing the wire mesh 14 rigidly to its backing plate 12 before the abrasive body is interlocked therewith. In the preferred construction, the wire mesh is welded directly to the steel plate 12 at suitably spaced points. This may be done by laying the wire mesh, such as an expanded metal sheet or a woven wire cloth, on the steel plate 12; and then by suitable welding apparatus, such as an electric arc welder in which the electrode provides the needed welding metal, the wire mesh is integrally attached to the backing plate by the welding metal 22 deposited at a number of spaced

points. The wire mesh, after it has thus been integrally secured to the backing plate, presents many interlocking surfaces for engagement with the under or near portion of the abrasive body.

At least one, and preferably several screws, studs or bolts 24 or other equivalent fastening devices are arranged to secure each backing plate 12 to the disk 16. These are located in a suitable spacing, and they have their heads 25 countersunk in the backing plate 12. The bolts project downwardly for insertion through suitable holes in the steel plate on which the segments are to be mounted and they are held in place by nuts 26. These bolts are put into place in the backing plate before the abrasive mass 10 is molded around the wire mesh. It will, therefore, be appreciated that the clamping or securing bolts 24 are independent of and lie wholly below the wire mesh and they do not engage it to any material extent, hence they cannot transmit any clamping stress to the wire mesh.

It will be observed that the abrasive body may be worn away down to the wire mesh since there are no obstructing members or securing devices above that wire mesh which can interfere with the grinding operation. This gives a maximum use of the abrasive for a given thickness of the body 10. The apertures in the expanded metal or wire screen, herein termed "wire mesh," which is used for the reinforcement may be of any suitable size, such as 1" mesh or smaller. An expanded metal mesh with diamond shaped openings $1\frac{1}{2}'' \times \frac{3}{4}''$ is suitable for an abrasive body which is a foot or larger in radial extent. The number of spots of welding metal between the wire mesh and the metal plate 12 may be as required to give a sufficiently rigid structure, but 25 or 30 welds are sufficient for an abrasive body of the above described size. The metal plate 12 may be comparatively thin such as $\frac{1}{4}$ or $\frac{1}{8}$ inch, it being merely thick enough to hold the abrasive

body rigidly in position and to clamp the same securely on the grinding plate 16. The wire mesh may be secured integrally to its backing plate by brazing or soldering it in position, and such procedures are to be considered as equivalents of the welding above described, it being evident that the method best suited for the construction will depend on the types of metals employed.

Various advantages in this construction will be 10 readily apparent; and it will be appreciated that many modifications may be made in the construction without departing from the scope of the appended claims.

I claim:

1. A grinding wheel comprising a rotatable supporting plate, a metal backing plate, a wire mesh integrally secured directly to the backing plate surface by welding metal at spaced locations and having interlocking portions therebetween, a body 15 of bonded abrasive material molded on the plate and embedding and interlocking rigidly with said portions of the wire mesh, said welding metal holding the wire mesh and the abrasive permanently immovable relative to the plate, and spaced 20 fastening devices located beneath and independent of the wire mesh and molded body which secure the two plates together without imposing strain on said body.

2. A grinding wheel comprising a rotatable support, 30 a set of abrasive segments shaped to form an annulus for mounting on said support, each segment having a metal backing plate, a wire mesh integrally secured to each plate at spaced spots by welding metal, a body of bonded abrasive material permanently molded on the plate and embedding and interlocking rigidly with the wire mesh, and fastening devices independent of the abrasive bodies which removably secure the plates 35 of said segments on the support.
